STEAM HEATING SYSTEM

Elmer Paul Harrison, Chicago, Ill., Orville A. Hunt, Oklahoma City, Okla., and Louin Tiller, Chicago, Ill., assignors, by direct and mesne assignments, to Reconstruction Finance Corporation, Chicago, Ill., a corporation of the United States

Application October 4, 1947, Serial No. 777,894

16 Claims. (Cl. 237—9)

1

This invention relates to heat exchange systems employing steam for processing materials, such as steam systems in laundries, paper mills, and other industries.

The invention pertains particularly to improvements in steam systems such as described in the Harrison and Hunt Patent No. 2,366,332, the copending application of Harrison and Hunt Serial No. 581,586, filed March 8, 1945, entitled "Heat Exchanger System," and the abandoned application of Tiller and Hunt Serial No. 762,628, filed July 22, 1947, entitled "Steam System." The present application is a continuation in part of the abandoned application of Harrison et al., Serial No. 701,252, filed October 4, 1946, entitled "Steam Heating System." The four mentioned disclosures are hereby incorporated in the present disclosure by reference insofar as consistent herewith.

Other copending applications disclosing the subject matter related hereto are: S. N. 78,605, filed February 26, 1949; S. N. 78,843, filed February 28, 1949; S. N. 78,842, filed February 28, 1949; S. N. 78,604, filed February 26, 1949; and S. N. 80,802, filed February 28, 1949.

A steam system of the type here involved is characterized by open channels for continuous flow from the steam supply through the equipment steam chests to the end of a return line in combination with thermostat means to release fluid from the return line into a region of lower pressure in a controlled manner to maintain a desired velocity level or average throughout the system. In the preferred practices of the invention a master control for regulating such release from the return line includes a receiver for fluid returned from the steam system and/or new water for the system.

The volume or rate of fluid release from the return side of the steam system is sufficient to minimize condensate in the system and to maintain a high rate of heat transfer to the material being heated. The master control is adjustable and the optimum rate of release for which the master control is set varies among installations. The act of adjusting the master control with respect to the rate of release from the return side of the system is aptly referred to as tuning the master control unit. The inherent range of adjustment should be extensive to make the mas-

2

ter control readily adjustable to different steam systems and different operating conditions.

One of the general objects of the present invention is to provide an augmented tuning range for the master control and to provide means and methods for applying the principles of the invention to a wide range of steam systems.

In some practices of the invention this general object is attained by the introduction of a modifying factor in the functioning of the master control. One example is the introduction of a cooling fluid to modify the action of a thermostat-controlled valve that controls the release of fluid from the return side of the steam system. Another example of introducing a modifying factor is the use of a heat exchanger to cause condensation of vapor in the return side of the system upstream from the thermostat valve so that velocity of flow through the steam system is promoted not only by the action of the thermostat valve but also by the action of the heat exchanger.

In other practices of the invention a modifying factor and a new combination of functions is provided by regulating the rate at which fluid is released from the receiver. The pressure in the receiver is determined, on the one hand, by the rate at which fluid is released into the receiver from the return side of the system and, on the other hand, by the rate at which fluid is released from the receiver. The thermostat for controlling release into the receiver responds to temperature changes in the receiver, which temperature changes, of course, vary with pressure changes. The temperature setting of such a thermostat is one tuning factor and the rate at which fluid is released from the receiver is a modifying factor which, taken with the first factor, affords a wide range of adjustment.

The fluids released from the receiver may be utilized in any desirable manner. For example, steam and/or condensate from the receiver may be used for preheating and deaerating make-up water. In this regard one embodiment of the invention comprises a novel arrangement of a receiver and a remote deaerating feed water heater.

A further object of the invention in certain of its practices is to favor the creation of pressure changes, velocity surges and pulsations in the

system for the sake of certain beneficial results.

Other objects and advantages of the invention will be apparent in the description to follow, taken with the accompanying drawings.

In the drawings, which are to be regarded merely as illustrative:

Fig. 1 is a diagrammatic view illustrating one embodiment of the invention;

Fig. 2 is a diagrammatic view showing certain details of the master control in Fig. 1;

Fig. 3 is a fragmentary sectional view showing how an orifice member may be employed in the system;

Fig. 4 is a fragmentary diagrammatic view indicating how air instead of water may be used for the cooling fluid;

Fig. 5 is a fragmentary diagrammatic view of a master control employed in a modified form of the invention;

Fig. 6 is a diagrammatic view representing a steam system incorporating the master control of Fig. 5.

Fig. 7 is a fragmentary view similar to Fig. 1 showing how the arrangement shown in Fig. 1 may be modified;

Fig. 8 is a diagrammatic view of another embodiment of the invention;

Fig. 9 is a diagrammatic view of an embodiment of the invention combining a receiver under pressure with a remote cooperating deaerator;

Fig. 10 is a diagrammatic view of an embodiment of the invention using a jet-compressor; and

Fig. 11 is a diagrammatic cross-section of the jet-compressor.

Fig. 1 shows, by way of example, the invention incorporated in paper drying machinery having a plurality of heat exchangers in the form of driers or cylinders 10. The web of paper to be dried moves in the direction indicated by the arrow 11 and makes successive contact with the rotating cylinders 10.

A boiler 12, or equivalent steam source, delivers steam through a suitable supply line 13 to a supply header 14, and the various cylinders 10 are connected in parallel to the supply header by suitable feed pipes 15. Each of the feed pipes 15 communicates with the corresponding cylinder 10 through the trunnion of the cylinder, as indicated in Fig. 2, and condensate is discharged from the cylinder through a suitable discharge pipe 17 that extends through the same trunnion of the cylinder and through a portion of the feed pipe. The discharge pipe 17 of each cylinder leads to a suitable return header 18.

In accord with a common practice it is contemplated that the outflow from each of the cylinders 10 will be restricted relative to the inflow to the cylinder for the purpose of proper steam distribution among the cylinders and for maintenance of the desired pressure differential between the supply header 14 and the return header 18. In the described arrangement the discharge pipe 17 from each drying cylinder 10 is sufficiently smaller in diameter than the corresponding supply pipe 15 to provide the desired restricting effect, but in some practices of the invention the restriction in the outflow from each drying cylinder may be provided, either by a valve or by an orifice member. Fig. 3, for example, shows an orifice member 20 in a discharge pipe 21, the orifice member being housed in a suitable fitting, generally designated 22.

Preferably the heat exchangers or drying cylinders 10 are grouped into subdivisions or

banks of cylinders. Such grouping may be accomplished by, in effect, providing separate return headers for each subdivision. In the construction shown in Fig. 1, instead of providing structurally separate return headers for the various banks we employ the single return header 18 but incorporate therein suitable valves whereby the header may be divided into functionally separate sections. Thus the twenty-four drying cylinders 10 shown in Fig. 1 may be grouped into four subdivisions or banks of six cylinders each by closing three valves designated 25, 26 and 27.

A feature of the arrangement shown in Fig. 1 is adjustability with respect to the grouping of the drying cylinders 10 into subdivisions or banks. Thus, by opening valves 25, 26 and 27 and closing valves 28, 29 and 30, the drying cylinders will be regrouped into banks comprising four, five, seven and eight cylinders, respectively. In such regrouping it will be noted that there is a relatively small number of cylinders in the first bank reached by the traveling paper, which cylinders are known as wet rolls, and a relatively large number of cylinders or dry rolls in the last bank. Since more steam is condensed on the wet end of the series than on the dry end, this grouping tends to equalize the amount of condensate that must be carried away from each of the return header sections.

The four sections of the return header 18 are connected with a master control, generally designated 31, by means of four individual return lines 32, respectively. As shown in Figs. 1 and 2, the master control 31 includes a receiver tank 36, and four control or release valves 37 in the four return lines 32, respectively, operated by four corresponding thermostats 38. The receiver tank may be at substantially atmospheric pressure, or at some pressure above atmospheric. In this instance it is assumed that a vent line 40 for the receiver tank is suitably adapted to maintain a moderate pressure in the tank.

Each of the return lines 32 may be provided with a suitable check valve 83 and a manually operable valve 84. Preferably each of the return lines 32 is also provided with a suitable strainer. Fig. 2 shows a well-known Y-strainer 85 which may be flushed whenever desired by opening a valve 86 in a pipe 87. As indicated in Fig. 2, the flushing action may be directed into the receiver 36 or may be directed through a branch pipe 88 to waste.

In the particular arrangement shown in Fig. 1, condensate discharged into the receiver tank 36 by the four return pipes 32 is conveyed from the tank by a pipe 41 to a pump 42, and is forced by the pump through a pipe 43 to a suitable feed water tank 45. The pump 42 operates continuously, but whenever the liquid level in the receiver tank 36 drops to a predetermined minimum level a cut-off valve 46 in the pipe 43 is closed automatically by a float controlled means 47, whereupon the condensate discharged from the pump 42 is recycled through the receiver by virtue of a by-pass line 48 equipped with a relief valve 49. The relief valve 49 is spring loaded to maintain a closed position, but opens in response to the pressure rise in the discharged condensate that results from closing of the cutoff valve 46.

New water to make up for losses in the system is delivered to the feed water tank 45 through a supply pipe 50, the supply pipe being equipped with a float controlled valve 52 that opens in response to lowering of the water level in the

feed water tank. From the feed water tank a suitable boiler feed pump 53 replenishes the boiler 12 through a feed line 55 in response to the usual automatic means (not shown) controlled by the water level in the boiler.

The specific construction of the master control 31 may be understood by referring to Fig. 2. It will be noted that the bulb 56 of the thermostat 38 that contains the usual volatile fluid for operating the corresponding release valve 37 is in a pipe 57 on the discharge side of the release valve, and that the pipe 57 is larger in diameter than the return line on the inlet side of the release valve, so that the released fluid has space in which to expand. The relationship between the thermostat and the valve is such that the valve closes, or at least partially closes, in response to increasing temperature, and opens, or at least opens to a greater degree, in response to decreasing temperature, the relationship being adjustable to cause the valve to open and close at selected temperatures. Thus the release will be in a pulsating manner, the release being by pulsating continuous flow if the valve merely fluctuates between two open positions and being by pulsating intermittent flow if the valve actually closes.

The pipe 57, housing the thermostat bulb, communicates with one or more downwardly directed spray heads 58, and it is important for the purpose of the invention that the small discharge apertures of the spray heads have sufficiently low flow capacity to restrict the outflow from the pipe 57 relative to the inflow. In other words, the discharge capacity of the release valve 37 is so much greater than the discharge capacity of the spray heads that prolong discharge from the release valve into the pipe 57 will cause a pressure rise in the pipe. Because of this action the pipe 57, in combination with the spray head 58, may be aptly termed a pressure accumulation chamber.

The critical temperature of each thermostat 38, or the temperature at which the thermostat is adjusted to cause opening action or closing action of the corresponding release valve 37, is above the normal temperature of the receiver tank 36 and below the temperature prevailing in the corresponding return line on the inlet side of the release valve 37, so that opening action of the release valve occurs automatically as the temperature in the accumulation chamber drops toward the normal temperature and closing action occurs automatically as the fluid released into the pressure accumulation chamber raises the temperature therein toward the temperature level in the corresponding return line that supplies the valve. By virtue of this arrangement the release valve causes pulsating flow in the system.

By way of example let it be assumed that the normal pressure of the condensate and steam on the inlet side of the release valve 37 is approximately thirty-two pounds, with the condensate at the corresponding temperature of 277° F.; that the pressure in the reservoir tank 36 is on the order of six pounds maximum, with a corresponding temperature of 230° F.; and that the thermostat setting is 255° F. As heretofore stated, prior to opening action of the release valve 37 the pressure and temperature in the pressure accumulation chamber approximate the pressure and temperature in the receiver tank. Upon opening action of the release valve 37, however, condensate, or a mixture of condensate and steam, is introduced into the pressure accumula-

tion chamber in large amount and with drop in pressure. The drop in pressure, of course, causes at least a portion of the condensate to flash into steam. As a result of the fluid introduction and of vaporization of the introduced fluid on one hand, and on the other hand the restriction of outflow by the spray apertures, the pressure in the pressure accumulation chamber rises with corresponding rise in temperature. When the temperature reaches approximately 255° or more, depending upon the lag in the operation of the thermostat, the release valve 37 is automatically operated in a closing direction, and immediately the pressure and temperature in the pressure accumulation chamber recede to cause repetition of the valve-operating cycle.

Each of the thermostats 38 is "tuned" or adjusted empirically to cause an overall or average rate of fluid release from each bank of drying cylinders sufficient to minimize condensate on the cylinder walls. Usually temperature and pressure readings are taken at various parts of the system and along the traveling paper for guidance in ascertaining the optimum setting of each thermostat 38. The thermostat setting is raised, of course, to increase the rate of fluid release, and is lowered to decrease the rate of release.

Since each valve 37 operates intermittently the increases in the overall or average rate of release by the valve may be raised either by increasing the frequency of the opening operations of the valve or by prolonging the periods of release or maximum release by the valve, or by increasing both the frequency and duration of valve operation. The raising of the temperature setting of a thermostat increases the rate of release flow by both of these expedients, since the higher the relative temperature in the pressure accumulation chamber when the valve closes, the more rapid is the subsequent drop in temperature to cause repetition of the valve operating cycle, and the higher the temperature required to close the valve the longer is the period required for that temperature to be built up in the pressure accumulation chamber. Preferably a combined pressure gauge and thermometer 59 is provided to indicate the pressure and temperature prevailing inside the pressure accumulation chamber or pipe 57.

The range of variation in the rate of fluid release by a valve 37 that may be covered simply by manipulating the setting of the corresponding thermostat 38, which range is adequate for many installations, is limited by the pressure and temperature prevailing in the receiver tank 36 and the pressure and temperature prevailing in the return line 32 above the valve 37. On the one hand, the temperature setting of the thermostat 38 must be lower than the normal temperature above the release valve to cause the valve to be closed automatically in response to heat provided by the released fluid, and, on the other hand, the thermostat setting must be above the normal temperature in the receiver tank 36, because otherwise the temperature in the pressure accumulation chamber would never drop sufficiently to open the valve.

If greater fluid release or more frequent fluid release is required for a given installation than is available within the practical range of thermostat adjustment, it is necessary to change some factor other than the temperature setting of the thermostat, or to introduce some new factor. Among the factors that conceivably could be

changed are the rate at which fluid is released at the maximum open position of the valve and the restriction of flow by the spray nozzles. It has been found, however, that any change in these two respects involves conflicting or complicating factors. For example, increasing the rate of flow through the valve at the maximum open position of the valve increases the rate at which the temperature in the pressure accumulation chamber rises, and thereby shortens the valve operating cycles. Decreasing the size or number of the spray apertures to hasten the rise in temperature for opening action of the valve, thereby to raise the overall rate of fluid release, tends to defeat its purpose by restricting the capacity of the spray heads to handle the increased volume.

Wherever this dilemma is met the present invention solves the problem by the application of a cooling fluid to the thermostat 38, thereby introducing a factor that modifies other involved factors in a desirable manner. The application of a cooling fluid to the thermostat hastens the drop in temperature of the thermostat following closing of the valve, and thereby increases the frequency of the valve opening operation. When the valve is open to introduce the released fluid into the pressure accumulation chamber the applied cooling fluid prolongs the period of flow or maximum flow in two ways: first, by modifying are retarding the heating effect of the released fluid, i. e., retarding a rise in temperature in the pressure accumulation chamber, and second, by counteracting to an appreciable extent the flashing of the released condensate with consequent retardation in the rate of pressure rise in the accumulation chamber.

The cooling fluid may be applied in various ways in various practices of the invention. A feature of the particular arrangement shown in Figs. 1 and 2 is the recycling of condensate from the receiver tank 36 for this purpose. In the construction shown the means for recycling the condensate includes a pipe 60 that branches from the pipe 43 between the pump 42 and the cut-off valve 46. To insure sufficient pressure for adequate flow in the pipe 60 a pressure regulator valve 61 may be inserted in the pipe 43 beyond the cut-off valve, if desired, so that when the cut-off valve is open substantial pressure on the discharge side of the pump 42 will prevail. It is to be understood, however, that the pressure regulator valve 61 is not essential. The pressure setting of the regulator valve 61 will, of course, be less than the pressure setting of the relief valve 49 in the bypass 48.

The recycled condensate may be conducted to a suitable heat exchanger 62, where it is cooled by new water, the new water being supplied to the heat exchanger through a pipe 63 and being discharged therefrom into the previously mentioned supply pipe 50. From the heat exchanger 62 the condensate passes into a pipe 65 which, by preference, is equipped with an intermittently operated valve 66, although such valve may be omitted.

The valve 66 may be operated periodically in any suitable manner. The particular arrangement shown in disclosed in the previously mentioned copending application Serial No. 581,586, and includes a solenoid 67 that operates the valve in one direction in opposition to a return spring 68. The circuit for energizing the solenoid 67 is controlled by a suitable relay 70 in a control circuit 71 governed by a suitable timer 72, the

timer being adjusted to vary the frequency and/or duration of the open valve periods.

The pipe 65 that is controlled by the valve 66 is in effect a manifold for supplying cooling fluid for each of the four thermostats 38, the cooling fluid being supplied through four corresponding branch pipes 73 equipped with individual adjustable valves 75. Preferably, as shown in Fig. 2, each of the pipes 51, comprising a part of the corresponding pressure accumulation chamber, is enlarged to provide an annular space 76 surrounding a jet nozzle 77 and a Venturi throat 78, and the corresponding branch pipe 73 communicate with this annular space. By virtue of this arrangement the fluid released from the valve 37 draws in the cool condensate from the branch pipe 73, and the condensate immediately enters into intimate mixture with the fluid released by the valve.

It is apparent that tuning of the master control 31 in the improved arrangement is quite flexible, since both the thermostats 38 and the four recycling valves 75 may be adjusted. In addition the cooling of the condensate by the heat exchanger 62 may be adjustable, but usually such additional adjustment is not at all necessary because manipulation of the thermostats 38 and the valves 75 cover such a wide range of rates of fluid release. Adjustments may be made over the augmented tuning range with surprising precision.

Often the prevailing temperature in the receiver tank 36 is low enough relative to the temperature prevailing on the inlet sides of the release valves to make cooling of the recycled condensate unnecessary, so that in many instances the heat exchanger 62 may be omitted. The intermittent valve 66 may also be omitted. The use of such an intermittent valve, however, results in abrupt changes in the cooling action and causes abrupt pressure changes in the steam system. The abrupt pressure changes or pressure waves in the steam system have been found to have a highly desirable effect in increasing the rate of heat transfer in the various drying cylinders 10.

Fig. 4 indicates how air, instead of condensate, may be employed as the cooling liquid to introduce a modifying factor for increasing the inherent tuning range of the master control. The structure involved is largely identical with the structure heretofore described, as indicated by the use of corresponding numerals to identify corresponding parts. Instead of introducing cooling condensate into the pipe 51 to affect the thermostat 38, a blower or fan 80 is positioned to direct cooling air against the exterior of the walls enclosing the thermostat 38. Obviously the cooling stream of air will have the same general effect as the previously described cooling stream of condensate, but usually to lesser degree. The fan 80 is driven by a suitable motor in a housing 81, and the speed of the motor is adjustable by a suitable variable control 82. In this arrangement tuning may comprise adjusting the speed of the blower 80 alone or in addition to adjusting the settings of the thermostats 38.

The invention may be embodied in other steam arrangements, as indicated by way of example in Figs. 5 and 6. Fig. 5 shows a master control, generally designated 89, including an upright receiver tank 90, and Fig. 6 is a simplified diagram illustrating how such a master control may be incorporated in a steam system.

Fig. 6 shows the master control tank 90 connected to a feed water supply pipe 91 and connected to a boiler 92 by means of a boiler feed pump 93 and a pipe 94. The pump 93 may vary

in operation in response to changes in the boiler water level by virtue of suitable automatic control means (not shown), or may operate at constant speeds subject to adjustment from time to time.

The boiler is connected by a steam line 95 to one or more heat exchangers, Fig. 6 showing two heat exchangers 96. Instead of valves or orifice members at the outlet sides of the two heat exchangers, the drawings show short lengths of relatively small pipe 97. The small pipes 97 are inserted in branches of a return line 98 that carries condensate and steam from the heat exchangers to the master control 89. Preferably, but not necessarily, a receiver tank 99 is inserted in the return line 98, as indicated, the receiver tank being closed from the atmosphere. Thus a clear trap-free channel is provided for the flow of steam from the boiler to the master control.

As shown in Fig. 5 the master control tank 90 contains heated deaerated water having a normal upper level 100 determined by a float 101 controlling a valve 102 in the water supply line. Preferably an overflow pipe 103 is connected to the master control to keep the water level from rising substantially above this upper level 100. When the water drops in level the float automatically opens the valve 102 to restore the water level. An auxiliary throttling valve 104 may also be placed in the water line, as shown.

The new water from pipe 91 passes through a condenser unit 105 having multiple ducts with exterior fins, the unit serving both to condense water vapor in the master control and to heat the new water initially. A suitable hood 106 may be provided to cause ascending water vapor to pass through the unit 105, non-condensable gases escaping through the vent 107 at the top of the master control.

From the condenser unit 105 the new water passes through the valve 102 and then into a mixing passage or pipe 108 that terminates in a plurality of downwardly directed spray or atomizing heads 109. The mixing passage provided by the pipe 108 corresponds in function to the previously mentioned pressure accumulation chamber in the first described form of the invention. Preferably a drip pan 110 is placed adjacent the mixing pipe 108 to receive heat therefrom, the drip pan catching droplets of condensate from the unit 105 and overflowing onto the body of water below. Heating the water in the drip pan results in the release of non-condensable gases from the water.

The return line 98 of the system is connected to an injector or nozzle 111 directed into the mixing pipe 108, the flow of steam and condensate to the nozzle being controlled by a thermostat valve 112 in the return line. The valve 112 opens in response to lowering of the temperature in the mixing pipe 108 to a predetermined minimum and closes in response to rise of the mixing pipe temperature to a predetermined maximum, being adjustable for various temperature settings. For such response the thermostat valve 112 is provided with a control tube terminating in a thermostat bulb 113 inside the mixing pipe 108. Preferably, as shown in Fig. 5, the spray nozzles 109 are higher than the portion of the mixing pipe 108 housing the thermostat bulb 113 to favor normal envelopment of the bulb by a residue of water when both valves 102 and 112 are closed.

The desired cooling fluid for introducing the modifying factor into the tuning combination

5 may be supplied by a suitable pipe 115, connected with the pipe 108 adjacent the injector nozzle 111. The cooling fluid may be obtained from any suitable source and may be circulated by any suitable means. In the particular construction shown the condensate accumulated in the bottom of the tank 90 is recycled through the pipe 115 by a suitable pump 116, and the rate of recycling flow is controlled by a suitable valve 117.

10 In the described arrangement shown in Figs. 5 and 6, the setting of the thermostat is, of course, substantially above the normal temperature prevailing in the master control tank 89, so that in the absence of any cooling aids whatsoever the thermostat bulb 113 would drop in temperature to a point at which the thermostat valve or release valve 112 would be opened. A continuous cooling effect on the thermostat bulb is added by the condensate continuously recycled through the pipe 115, the modifying effect being the same as heretofore described.

15 An additional cooling effect which automatically varies with the heat load on the system is afforded by the new water that is introduced into the mixing pipe 108 whenever the float controlled valve 102 is open. The operation of the valve 102 follows variations in the heat load, since increasing the heat load increases the demand for new water and therefore increases the amount 20 of new water released into the pipe 108 by operation of the float 101. It is to be noted, moreover, that whenever condensate removal from the system tends to slow down, the liquid level 100 in the master control tank 90 tends to drop thereby 25 to cause the control valve 102 to introduce new water with consequent cooling effect on the thermostat bulb. Such cooling action hastens opening of the valve 112 to hasten the removal of the condensate accumulated in the system. The 30 cooling effect of the new water may be prolonged by simply throttling the flow of the new water through the valve 102, the throttling action being accomplished in an adjustable manner by the valve 104.

35 45 It is apparent that the system shown in Figs. 5 and 6 has all of the advantages of the first described system, and the added advantage of automatically releasing steam in response to the addition of new water whereby the release of 50 steam is desirably increased to a substantial extent whenever the heat load on the system is increased.

Opening and closing action of the thermostat valve 112 creates beneficial pressure pulsations 55 and velocity surges in the steam system. To increase the number of such pulsations and surges, suitable means may be provided to continually and automatically interrupt the flow of new water when the float 101 is down. Fig. 5 shows a solenoid valve 120 in the water supply pipe 91 for this purpose.

60 The solenoid valve 120 is in series with an automatic electric timer 121, and a mercury switch 122. The circuit is traced as follows: lead 123, solenoid valve 120, wire 124, timer 121, wire 125, mercury switch 122, and lead 126.

65 The mercury switch 122 is mounted on the float control mechanism to rock to a circuit closing position whenever the float 101 drops sufficiently to open the float valve 102. Thus whenever the float valve 102 opens the solenoid valve 120 is operated to repeatedly interrupt the flow 70 of cooling water to the thermostat bulb 113. Such intermittent water flow causes the thermo-

11

stat valve 112 to open and close repeatedly while the float 101 is down.

The timer 121 may be of any suitable type. In one practice, the timer 121 is a well known control device that is adjustable to divide a 30 second period into an open valve period and a closed valve period in any desired proportion. For example, the solenoid valve 120 may open for ten seconds and close for 20 seconds in repeated cycles of operation.

Fig. 7 shows an arrangement for using water other than recycled condensate for cooling the thermostat bulb. If soft water is available from the general water supply or if it is feasible to use water that has been treated for use in the steam system, this arrangement is suggested.

The structure shown in Fig. 7 is largely identical with the structure shown in Fig. 1, as indicated by the use of corresponding numerals to designate corresponding parts. The new water for cooling the bulbs is supplied through the previously described cooling water manifold 65, and may be periodically interrupted by the timer-controlled valve 66. The condensate mixed with the introduced cooling water in the receiver 36 is delivered to the pipe 43 by the previously mentioned pump 42 as heretofore described.

The receiver 36 may be under substantial pressure and the pipe 43 may lead directly to the boiler so that the condensate throughout the steam condensate cycle is maintained at relatively high pressure to avoid heat losses by excessive flashing. In all practices of the invention, the fluid released from the receiver by the vent arrangement may be used for various heating purposes. Examples of such use will be described later.

The purpose of Fig. 8 is to illustrate how the action of cooling water on thermostat bulbs for promoting and controlling velocity in the return lines of the steam system may be supplemented by heat exchangers in the return lines for the same purpose.

Fig. 8 shows a master control 31 including a receiver 36 provided with a vent release 130. The vent release may serve, for example, to maintain a pressure on the order of 10 to 30 pounds in the receiver. The usual return lines 32 are connected with the receiver 36 through the usual thermostat-controlled valves 37 and water for cooling the thermostat bulbs is supplied through a cooling header 65 as heretofore described.

Each of the return lines 32 is provided with a heat exchanger 131 through which cooling water flows for the purpose of causing condensation of steam in the return line. Such condensation means that the fluid shrinks to only a fraction of its vapor volume, and, of course, such contraction in volume promotes flow in the return line.

It is apparent that a cooling fluid from any suitable source may be employed in the series of heat exchangers 131 and that the cooler the medium the greater the flow-promoting effect. In the particular arrangement shown in Figure 8, the cooling fluid is supplied by a conventional water treating apparatus which may not only treat the water but also deaerate the water.

The treated water under pressure and at, say, 220° F. flows through a pipe 132 having two branches 133 and 135. The branch 133 passes through a heat exchanger 136 where the water is cooled to say 185° and then enters the previously mentioned manifold 65 for cooling the thermostat bulbs controlling the valves 37. A suitable valve 137 operated by a float 138 may be pro-

12

vided to cut off the flow of cooling water whenever the liquid in the tank 36 reaches a predetermined maximum level. This arrangement insures that the receiver will not be flooded.

The heat exchanger 136 may be supplied with a cooling medium in any suitable manner. In the particular arrangement shown, new water to supply the water treating apparatus is used. The new water enters the heat exchanger 136 through a pipe 140 and is carried off to the treating apparatus by a pipe 141.

The second branch 135 of the previously mentioned pipe 132 that supplies the treated water is provided with a suitable check valve 142 and is connected to the intake of a boiler feed pump 143. Liquid that accumulates in the receiver 36 is drawn off by a suitable pump 145, the output of which is carried by a pipe 146 to the previously mentioned pipe 135. Thus liquid from the receiver 36 is continually supplied to the intake of the boiler feed pump 143. The pump 143 discharges into a boiler line 147 which has a number of branches, there being six branches 148 leading to the six previously mentioned return line heat exchangers 131 respectively and one branch 149 that by-passes all of the heat exchangers. The by-pass branch 149 connects with a pipe 150 that leads directly to the boiler. A pipe 151 is connected to all of the heat exchangers 131 to pick up the cooling water from the heat exchangers for delivery to the boiler pipe 150.

It will be noted that the fluid pumped into the boiler feed line 147 for passage through the various heat exchangers 131 on its way to the boiler is make-up water mixed with condensate that has been returned through the various return lines 32.

Preferably the branch pipes 148 and 149 are provided with respective valves 152, which valves 40 may be individually manipulated to vary the relative amounts of water that flow through the various heat exchangers 131. If there is reason 45 for promoting velocity in one or more of the return lines 132 relative to the other return lines, the proportion of cooling water that flows through the corresponding heat exchanger or heat exchangers may be increased accordingly by manipulating the appropriate valve or valves 152.

A further possibility for increasing the velocity 50 of flow through any one of the return lines 32 is to adjust the corresponding thermostatic valve 37 at a higher setting than the rest of the valves to favor opening action of the valve. If desired, flow through any selected return line may be 55 increased relative to the flow through the remaining return lines by resorting to both of these methods of adjusting, that is to say, by increasing the flow of cooling water through the corresponding heat exchanger 131 and at the same 60 time raising the temperature setting of the corresponding thermostatic valve 37. The settings of the thermostats may be graduated in accord with a graduated series of rates of flow or in accord with the quantities of condensate to be handled 65 by the various return lines.

Fig. 9 is illustrative of various practices of the invention that involve utilizing steam from the receiver 36. The steam may be largely live steam drawn through the whole system or may be 70 largely if not entirely, steam generated by the flashing action of condensate as it drops in pressure on entering the receiver.

Fig. 9 shows the usual master control 31 including the usual receiver 36. The various return 75 lines 32 are connected to the usual thermostat-

controlled valves 37 and a manifold 65 delivers cooling water to the thermostats as heretofore described. A suitable pump 153 may be operated continuously to deliver liquid from the master control tank 36 to a boiler feed line 155. In the particular arrangement shown, whenever the liquid content of the receiver 36 drops to a predetermined minimum level, a suitable float (not shown) in the tank opens a valve 156 in a by-pass line 157 from the discharge side of the pump 153 to the master control tank for recycling of the fluid. This arrangement keeps the receiver from being pumped dry.

Steam from the receiver 36 in Fig. 9 is continually released through a pipe 158 to a suitable point of use or disposal. A feature of the particular arrangement shown is that the steam is delivered to a low pressure steam-consuming device and the resulting condensate is employed to cool the thermostat bulbs. In Fig. 9 the pipe 158 carries steam from the master control tank to a low pressure heater 160 and the condensate from this heater is delivered by a suitable pump 162 to the previously mentioned cooling water manifold 65.

If desired, one or more expedients may be employed to insure that the liquid delivered to the manifold 65 is relatively cool. Thus Fig. 9 shows a pressure reducing valve 163 in the pipe 158 to drop the pressure of the steam supply to the heater 160. Such pressure drop means cooler condensate. A second expedient that may be used is a heat exchanger 165 for cooling the condensate as it passes through the manifold 65. Relatively cool water from any suitable source may be circulated through the heat exchanger 165 by means of pipes 166.

The various parts of Fig. 9 described up to this point may constitute a practical embodiment of the invention as will now be explained. The pressure in the receiver 36 will be determined on the one hand, by the rate at which fluid enters the receiver through the thermostat-controlled valves 37 together with the rate of inflow from the cooling manifold 65 and, on the other hand, by the rate at which steam is drawn off by the pipe 158. It is contemplated that the rate of withdrawal of steam from the receiver 36 through the pipe 158 will be suitably controlled to maintain the pressure in the master control tank in a selected range of pressures that the thermostat valves 37 will be adjusted to operate within the range of temperatures corresponding to that range of pressure. Preferably the settings of the various thermostat valves 37 will be graduated in accord with the condensate loads on the corresponding return lines 32, the higher the condensate load the higher being the setting of the corresponding thermostat valve.

For any given rate of fluid withdrawal from the receiver 36 by the condensate pump 153 and the steam line 158 the various thermostat valves 37 will release fluid from the return lines 32 at relative rates determined by the relative settings of the thermostat valves. The total release from the return lines under steady state conditions will tend to maintain some given equilibrium pressure with receiver. In practice the several thermostat settings must not extend over too wide a range otherwise the pressure in the master control tank will be sustained by the thermostat valves with the higher settings and the thermostat valves with the lower settings will not open at all.

The supply side of a steam system represented by Fig. 9 may be at 40 lbs. per square inch gauge.

The pressure in the return lines 32 may be approximately 35 lbs. and the pressure in the receiver 36 may be in the range of 10 to 30 lbs. gauge. If, for example, the master control tank is at 30 lbs., the pressure reducing valve 163 may serve to drop that pressure to approximately 12 lbs. gauge.

The plurality of thermostat valves 37 will respond automatically to any changes in the rate 10 of fluid released from the master control tank. Suppose, for example, that a state of equilibrium exists with a constant release of fluid from the tank and that the pressure in the tank is at 30 lbs. gauge. If, under these circumstances, the 15 steam release through the pipe 158 is increased, the valves 37 will automatically open to a greater extent to tend to prevent drop in the tank pressure and a new equilibrium pressure will be established in the tank, say a pressure of 28 lbs. gauge. 20 Conversely, if for any reason the rate of fluid release from the receiver is decreased, the pressure in the receiver will rise to a new equilibrium and the consequent higher temperature in the receiver will cause the thermostat valves to reduce the 25 release from the return lines. Each thermostat valve responds directly only to temperature changes as distinguished from pressure changes, but temperature in the receiver varies directly with steam pressure so that the valves respond 30 indirectly to pressure changes.

It is to be understood that in all instances the thermostat may be slow acting or quick acting and may completely close or only partially close.

In some practices of the invention steam may 35 be released from the receiver 36 through a pipe 167 leading to a remote deaerator tank 170, the release through the pipe 167 either supplementing the release through the pipe 158 or replacing the release through the pipe 158.

40 In Fig. 9 the master control tank is shown diagrammatically in plan but the deaerator is shown diagrammatically in elevation. The layout indicated in Fig. 9 is suggested for steam plants in which the logical and convenient point for the 45 collection of condensate by a receiver is a considerable distance from the boiler room where deaeration requiring considerable steam is carried out. The demand for steam for deaeration is met in part by the steam from the receiver.

50 In the particular arrangement shown in Fig. 9, the pipe 167 for conveying steam from the master control tank 36 is connected to a heat exchanger 171 in the boiler room and the heat exchanger in turn is connected to the deaerator tank 170 by a pipe 172, the connection being above 55 the liquid level in the deaerator tank. Cold water for make-up is supplied through a pipe 173, having a valve 174 that responds to a float control 176 on the deaerator tank. The water flows 60 through a condenser 177 for condensing vapors in the upper end of the tank and then passes through a pipe 178 to a coil 180 inside the heat exchanger 171. From the coil 180 the heated water is carried by a pipe 181 to a spray head 65 182 inside the deaerator tank above the point of discharge of the previously mentioned pipe 172. This spray head has downwardly directed spray openings so that the released water is directed towards the condensate or condensate and steam 70 that is discharged from the pipe 172.

The deaerator tank 170 has at the top a relief pipe 175 controlled by a relief or safety valve 176 set at some pressure higher than the normal pressure prevailing inside the deaerator tank. A 75 vent valve 186 in a vent pipe 187 leading to the

atmosphere may be a simple manual valve that is adjusted from time to time as required to permit continuous release of fluid at a rate to maintain a desired approximate normal pressure in the deaerator tank. It is contemplated that the arrangement and the various adjustments will be such that the fluid escaping to the atmosphere through the vent pipe 187 will be mostly, if not entirely more condensable gases isolated by the deaeration action.

Fig. 9 shows a pair of boiler feed pumps 190 and 191 connected in parallel to the bottom of the deaerator tank 170 by a pipe 193. The two pumps, one of which will serve as a stand-by pump, are connected to common discharge pipe 193 leading to the previously mentioned boiler feed line 155. If desired, a valve 195 in a by-pass pipe 196 may be opened to cause condensate from the receiver 36 to be delivered to the deaerator tank 170 instead of directly to the boilers. Also if desired a valve 197 in a by-pass pipe 198 may be opened to cause the cold water supply to go directly to the intake sides of the boiler feed pumps 190 and 191 instead of directly to the deaerator tank 170.

It is assumed in Fig. 9 that the pressure drop between the receiver 36 and the deaerator tank 170 caused by the relatively long pipe 167, the heat exchanger 171, and the pipe 172 will be such that the relative pressures in the two tanks will be at desired values. If a greater pressure difference is required than can be provided by normal flow resistance, a greater pressure drop may be provided by using restrictions or using a pressure reducing valve, which expedients are well known to the art.

In one instance, by way of example, the pressure in the receiver 36 may be 10 lbs. gauge and the pressure in the deaerator tank 5 lbs. gauge with a pressure drop of 5 lbs. between the two tanks and a final pressure drop of 5 pounds across the partially opened vent valve 186. Preferably the deaerator tank 170 is provided with a suitable pressure gauge 200 for guidance in adjusting the valve 186. In other instances the pressure in the master control tank may be relatively high, say 30 or 40 lbs. gauge, for the sake of direct return of condensate to the boiler without substantial reduction in the pressure of the condensate.

The deaeration action in the tank 170 is well known operation. The newly introduced water is heated in two stages: first, in the condenser 177 and second, in the coils 180 of the heat exchanger 171. The water reaches the spray head 192 at relatively high temperature and at greater pressure than the pressure prevailing in the deaerator tank.

The release of the heated water through the spray openings into the region of lower pressure causes separation of non-condensable gases from the water and further separation occurs as the spray encounters the heated discharge from the pipe 172. The cooling action of the spray is such as to condense substantially all the vapors released by the pipe 172 and any residual vapors that exist are turned into water by the condenser.

Fig. 10 illustrates diagrammatically another practice of the invention in which steam is continually drawn from the master control tank at a rate to maintain a predetermined pressure or range of pressures therein. The concept here is to employ a jet-compressor 205 to recycle the

steam from the master control receiver 36 through the supply header 206.

High pressure steam from a high pressure supply line 207 is supplied to the high pressure inlet of the jet-compressor 205 for discharge from an enclosed jet nozzle 208 (Fig. 11) into a Venturi throat 210. Steam from the receiver 36 is carried by a pipe 211 to the low pressure inlet of the jet-compressor 205 for intermixture with the high pressure steam in the venturi. The discharge from the jet-compressor 205 is carried by a pipe 212 to the supply header 206. The header 206 feeds the various cylindrical driers 10 which are constructed and arranged as herebefore described.

The driers 10 are grouped in the usual manner for delivering condensate to the receiver through a plurality of return lines. Fig. 10 shows a return header 18 connected to one of the return lines 32 and shows fragments of the remaining return lines. Each of the return lines 32 is controlled by the usual thermostat valve 37, and if desired, each of the thermostats may be supplied with relatively cool water to favor opening action of the valve as heretofore described. Condensate is continually withdrawn from the receiver 36 by the usual pump 42.

As an example of operating conditions, steam supplied to the jet-compressor 205 through the pipe 207 may be at 100 lbs. gauge and the receiver 36 may supply steam at approximately 40 lbs. gauge. The jet-compressor will supply steam to the header 206 at some intermediate value, say 60 lbs. gauge.

Preferably some provision is made for maintaining the desired pressure relationships automatically. For this purpose, Fig. 10 shows a pressure regulator 213 in the high pressure steam line 207. A tube 215 extends from the pressure regulator 213 for response to the discharge side of the jet-compressor 205 so that the pressure regulator may maintain a predetermined pressure differential across the jet-compressor. In addition, a suitable pressure reducing valve 216 may be inserted in the pipe 211 to release steam from the receiver 36 at a controlled rate that will insure maintenance of the desired back pressure in the receiver.

We claim as our invention:

50. 1. In a steam system, at least one steam using device, a steam supply connected with the inlet side of said device, a closed receiver, a return line from the outlet of said device to said receiver to carry fluid thereto, a valve controlling release of fluid from said return line into said receiver, said device and return line forming a continuous open channel from said steam supply to said valve, a thermostat operatively connected to said valve to cause opening action of the valve at temperatures below the thermostat setting and closing action of the valve at temperatures above the thermostat setting, said thermostat being positioned to be heated by the fluid released by said valve and having a setting above the temperature prevailing in said receiver and below the temperature prevailing in said return line, a device using steam at a lower pressure than said steam supply, means to supply flash steam from said receiver to said low pressure device and means to convey the condensate from said low pressure device into heat exchange relation with said thermostat for cooling of the thermostat.
60. 2. In a steam system, a combination as set forth in claim 1 in which said valve discharges into a passage leading to spray openings in said

receiver and in which said thermostat is positioned in said passage.

3. In a steam system, a combination as set forth in claim 1 in which means is provided to reduce the pressure of the steam supplied to said low pressure device substantially below the pressure in said receiver.

4. In a steam system, a combination as set forth in claim 1 in which heat exchange means is provided to cool the condensate before the condensate reaches said thermostat.

5. In a steam system, a plurality of steam using devices, a steam supply connected with the inlet sides of said devices, a receiver under substantially less pressure than said steam supply, a plurality of return lines from said devices to said receiver, a valve controlling the release of fluid from each of said return lines into said receiver, said devices and return lines forming continuous open channels from said steam supply to said valve, a thermostat operatively connected to each of said valves, said thermostat being positioned to be heated by the fluid released by the valve, said thermostat having a temperature setting above which it causes closing action of the valve and below which it causes opening action of the valve, said setting being below the temperature in the corresponding return line but above the temperature in the receiver, the settings of said thermostats being varied in accord with desired relative rates of flow in said return lines, and means to deliver fluid from said receiver at a rate to maintain the pressure and temperature therein below the pressure and temperature in said return lines.

6. In a steam system, a combination as set forth in claim 5 which includes means to apply a cooling fluid to said thermostats.

7. In a steam system, a combination as set forth in claim 5 in which each of said valves discharges into a corresponding passage leading to spray openings in said receiver and in which the corresponding thermostat is positioned in said corresponding passage.

8. In a steam system, a plurality of steam using devices divided into groups, a steam supply connected with the inlet sides of said devices, a receiver, a plurality of return lines from said groups respectively to said receiver, a valve controlling the release of fluid from each of said return lines into said receiver, said steam using devices and return lines forming continuous open channels from said steam supply to said valves, a thermostat operatively connected to each of said valves, said thermostat being positioned to be heated by the fluid released by the valve, said thermostat having a temperature setting above which it causes closing action of the valve, and below which it causes opening action of the valve, said setting being below the temperature in the corresponding return line but above the temperature in the receiver, a plurality of passages corresponding to said thermostats for conducting cooling fluid into heat exchange relation with the thermostats to cause opening action of the corresponding valves, and a plurality of valve means for varying the flow of the cooling fluid through said passages.

9. In a steam system, a plurality of steam using devices, a steam supply connected with the inlet side of said devices, a receiver, a plurality of return lines for conveying fluid from said devices to said receiver, a heat exchange means in each of said return lines for condensing action on vapor in the return line, a valve controlling the

release of fluid from each of said return lines into said receiver, said return lines and devices forming continuous open channels from said steam supply to said valves, a thermostat operatively connected to each of said valves, said thermostat being positioned to be heated by the fluid released by the valve, said thermostat having a temperature setting above which it causes closing action of the valve and below which it causes opening action of the valve, said setting being below the temperature in the corresponding return line but above the temperature in the receiver, and means to draw fluid from said receiver at a rate to maintain the desired pressure therein.

10. In a steam system, a combination as set forth in claim 9 which includes means to apply a cooling fluid to each of said thermostats.

11. In a steam system, a plurality of steam us-

ing devices, a steam supply connected with the inlet sides of said devices, a closed receiver, a plurality of return lines from said devices to said receiver, a valve controlling the release of fluid from each of said return lines into said receiver, said steam using devices and return lines forming continuous open channels from said steam supply to said valves, a thermostat operatively connected to each of said valves, said thermostat being positioned to be heated by the fluid released by the valve, said thermostat having a temperature setting above which it causes closing action of the valve and below which it causes opening action of the valve, said setting being below the temperature in the corresponding return line but above the temperature in the receiver, and means to draw flash steam from said receiver at a rate to maintain the pressure of the receiver within a given range below the pressure prevailing in said return lines.

12. In a steam system, a plurality of steam using devices, a steam supply connected with the inlet sides of said devices, a closed receiver, a plurality of return lines from said devices to said receiver, a valve controlling the release of fluid from each of said return lines into said receiver, said steam using devices and return lines forming continuous open channels from said steam supply to said valves, a thermostat operatively connected to each of said valves, said thermostat being positioned to be heated by the fluid released by the valve, said thermostat having a temperature setting above which it causes closing action of the valve and below which it causes opening action of the valve, said setting being below the temperature in the corresponding return line but above the temperature in the receiver, a deaerator tank remote from said receiver, means to remove flash vapor from said receiver to said deaerator, and means to remove condensate from said receiver, said two removing means maintaining the pressure in the receiver substantially below the pressure in said return lines.

13. In a steam system, a combination as set forth in claim 12 in which each of said valves discharges into a corresponding passage leading to spray openings in said receiver and in which the corresponding thermostat is positioned in said corresponding passage.

14. In a steam system, at least one steam using device, a steam supply, a jet-compressor having a discharge outlet connected to the inlet sides of said device, a high pressure inlet connected with said supply and a low pressure inlet, a closed receiver, a return line from the outlet of said

19

device to said receiver to carry fluid thereto, a valve controlling release of fluid from said return line into said receiver, said devices and return line forming a continuous open channel from said jet-compressor to said valve, a thermostat operatively connected to said valve to cause opening action of the valve at temperatures below the thermostat setting and closing action of the valve at temperatures above the thermostat setting, said thermostat being positioned to be heated by the fluid released by said valve and having a setting above the temperature in said receiver and below the temperature in said return line, means to convey steam from said receiver to said low pressure intake of the jet-compressor and means to release condensate from said receiver.

15. In a steam system, a combination as set forth in claim 14 which includes means to apply a cooling fluid to said thermostat.

10

5

20

16. In a steam system, a combination as set forth in claim 9 in which fluid from said receiver flows through said heat exchanger means for condensing action on the vapor in said return lines.
